PORTABLE SNOW FENCE

Hans Rieger, Munich, Germany

Application February 17, 1954, Serial No. 410,981

Claims priority, application Germany March 23, 1953

12 Claims. (Cl. 256—12.5)

This invention relates to fences, and more particularly to fences adapted to prevent the formation of snow-drifts, commonly referred to as snow fences.

In the past fences serving this function have been adapted; these fences however have either been constructed completely of wood resulting in a bulky cumbersome structure requiring continuous care and maintenance or have been constructed of wood pickets laced together by baling wire. They have been constructed for example of wood boards criss-crossed over each other with an occasional stake driven into the ground. These fences have been built on the spot where required and complete demolition occurs when taking the fences down after use for the winter. In more recent years in an attempt to avoid the difficulties involved in building a fence on the spot these fences have been made of wood pickets connected together by baling wire. The result obviously is a rather flimsy, structurally weak construction.

In the relatively rigid board fence of past years rotting becomes a great problem both at the point where the boards enter the ground due to the wetting effect of the earth on the wood and at the point where the boards are nailed together due to the collection of moisture at the nail joint. Difficulty is also encountered since the boards tend to become brittle under cold weather conditions whereby the wind loads during snowstorms cause considerable damage. The baling wire-wood picket construction is also subject to the above-mentioned difficulties.

In an attempt to overcome these difficulties the present construction has been evolved whereby conventional wire fencing may be employed permitting the use of galvanized weatherproof wiring. Clearly the use of such wire mesh fences would itself be inadequate in preventing the passage of snow. It is for this reason that flexible slats are interlaced between the apertures of the wire mesh thus forming a bulwark against the passage of the snow. Spaces between the slats permit the wind to pass through thus diminishing the wind load to be supported by the fence. The fence is maintained in position by means of periodically provided stakes or poles, thus keeping to a minimum the contact between fence element and earth and thereby diminishing the rotting effect of the moist ground on the fence.

It is accordingly a primary object of this invention to provide a fence and a method of building same which can keep back the snow so as to prevent snow drifts.

It is a secondary object of this invention to provide such a fence which is readily portable whereby it may readily be taken down after a winter's use and replaced at the beginning of the next winter season.

A further object of this invention is to provide a snow fence which can economically be constructed of the sturdiest fence material available.

A still further object of this invention is to provide a fence in which earth to fence contact is kept at a minimum thereby minimizing any rotting.

2

Another object of this invention is to provide a fence which may readily flex under wind load without breaking.

5 A still further object of this invention is to provide a fence in which the elements are readily replaceable with a minimum of effort when repair is needed.

With the above objects in view the present invention mainly consists of provision of an intermeshed wire fence supported on posts adapted to be inserted into the ground 10 spaced at lengths therealong and fastened thereto. Between these posts and interlaced in the mesh fence are provided snow retaining elements or slats.

The novel features which are considered as characteristic for the invention are set forth in particular in the 15 appended claims. The invention itself, however, both as to its construction and its method of operation, together with additional objects and advantages thereof, will be best understood from the following description of specific embodiments when read in connection with the accompanying drawings, in which:

Fig. 1 is a view of a length of the fence showing one species of the invention;

Fig. 2 is an enlarged view showing a section of the fence with another embodiment of the stake arrangement and 25 employing a different species of wire mesh;

Fig. 3 is a detail, drawn to a reduced scale, of the embodiment shown in Fig. 2; and

Fig. 4 is a cross-section taken on the line 4—4 of Fig. 3 through a slat shown in Fig. 3.

30 Referring more particularly to the embodiment of the disclosure shown in Fig. 1, it is seen that posts or stakes 1 are provided having pointed ends 2 so as to permit ready insertability into the ground. Supported on the stakes 1 is a length of wire fencing 3 of the mesh variety. 35 The particular mesh employed in the embodiment disclosed in Fig. 1 is of the type wherein the strands making up the mesh of the fence cross each other. Clearly the particular type of fence employed may be varied so long as a mesh structure results. Between the posts 40 or stakes 1 at spaced intervals along the length of fence 3 snow resisting elements or slats 4 are woven into the mesh. The particular orientation of the slats may be varied from a position at right angles to the ground to one parallel to the ground. In the preferred embodiment the most desirable arrangement has been illustrated, namely: a positioning of the slats at right angles to the ground. It is to be noted that the preferred construction has a slat spacing wherein the slats, which are 45 of a width equal to half that of the mesh, are arranged at least half a mesh width apart. The slats are preferably fastened to the wire fencing. In the preferred embodiment this fastening is disclosed as taking place by means of a strand of wire 5 extending through hole 6 at an upper portion of the slat fastened to upper wire 7 of the fence. It is illustrated as connected at the upper portion of the slat, since when construction takes place at the fence site it eliminates the need for the workmen to stoop excessively, but may either be woven into the fence without fastening, or tied at any other 50 convenient point.

60 The posts or stakes 1 are preferably made up of a light tubular metal. It should be obvious however, that though a preferred construction would employ a light tubular non-rustable material, stakes of any other variety may also be utilized.

65 In the embodiment of Fig. 2 it is to be noted that the fence is provided of a sectionalized structure whereby separate units may be maintained. Note the stakes at the right of Fig. 2 indicating how two fence units may 70 be joined. The disclosure of Fig. 2 also indicates the obviously permissible use of a different variety of wire meshing whereby the strands of the mesh interlace and

go back upon themselves. This mesh construction is most clearly indicated in Fig. 3.

The slats 4 may be formed of any light flexible material. Light non-ferrous metal strips or plastic or wood may be employed whichever is found most economically feasible.

It will be understood that each of the elements described above, or two or more together, may also find a useful application in other types of snow fences differing from the types described above.

While the invention has been illustrated and described as embodied in snow fences, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. In a fence adapted to be rolled up, in combination, a wire network formed by two groups of wire portions, the wire portion of each group being substantially parallel to each other and being inclined to the wire portions of the other group to form quadrangular wire meshes in said network; and a plurality of substantially parallel spaced slats each having opposite longitudinal edge portions and opposite faces extending between said edge portions, said slats being interwoven between and held by said two groups of wire portions, the wire portions of each group passing across one of said faces of said slats, and passing under the wire portions of the other group at one of said longitudinal edge portions of each slat and over the wire portions of said other group at the other longitudinal edge portion of each slat.

2. In a fence adapted to be rolled up, in combination, a wire network formed by two groups of wire portions, the wire portion of each group being substantially parallel to each other and being inclined to the wire portions of the other group to form substantially equal quadrangular wire meshes in said network; and a plurality of substantially parallel spaced slats each having opposite longitudinal edge portions and opposite faces extending between said edge portions, said slats being interwoven between and held by said two groups of wire portions, the wire portions of each group passing across one of said faces of said slats, and passing under the wire portions of the other group at one of said longitudinal edge portions of each slat and over the wire portions of said other group at the other longitudinal edge portion of each slat, said slats being substantially in the plane of said wire network when the latter is in a plane and said slats being substantially normal to a diagonal of said meshes and having a width smaller than half of said diagonal and being spaced from each other a distance larger than their width.

3. In a fence adapted to be rolled up, in combination, a pair of spaced substantially parallel wires; a wire network formed by two groups of wire portions, the wire portion of each group being substantially parallel to each other and being inclined to the wire portions of the other group to form quadrangular wire meshes in said network extending between said pair of parallel wires and said parallel wires interlaced with the wire meshes adjacent thereto; and a plurality of substantially parallel spaced slats each having opposite longitudinal edge portions and opposite faces extending between said edge portions, said slats being interwoven between and held by said two groups of wire portions, the wire portions of each group

passing across one of said faces of said slats, and passing under the wire portions of the other group at one of said longitudinal edge portions of each slat and over the wire portions of said other group at the other longitudinal edge portion of each slat.

4. In a fence adapted to be rolled up, in combination, a pair of spaced substantially parallel wires; a wire network formed by two groups of wire portions, the wire portion of each group being substantially parallel to each other and being inclined to the wire portions of the other group to form substantially equal quadrangular wire meshes in said network extending between said pair of parallel wires and said parallel wires interlaced with the wire meshes adjacent thereto; and a plurality of substantially parallel spaced slats each having opposite longitudinal edge portions and opposite faces extending between said edge portions, said slats being interwoven between and held by said two groups of wire portions, the wire portions of each group passing across one of said faces of said slats, and passing under the wire portions of the other group at one of said longitudinal edge portions of each slat and over the wire portions of said other group at the other longitudinal edge portion of each slat, said slats being substantially in the plane of said wire network when the latter is in a plane and said slats being substantially normal to a diagonal of said meshes and having a width smaller than half of said diagonal and being spaced from each other a distance larger than their width.

5. In a fence adapted to be rolled up, in combination, a pair of spaced substantially parallel wires; a wire network formed by two groups of wire portions, the wire portion of each group being substantially parallel to each other and being inclined to the wire portions of the other group to form substantially equal quadrangular wire meshes in said network extending between said pair of parallel wires and said parallel wires interlaced with the wire meshes adjacent thereto; a plurality of substantially parallel spaced slats each having opposite longitudinal edge portions and opposite faces extending between said edge portions, said slats being interwoven between and held by said two groups of wire portions, the wire portions of each group passing across one of said faces of said slats, and passing under the wire portions of the other group at one of said longitudinal edge portions of each slat and over the wire portions of said other group at the other longitudinal edge portion of each slat, said slats being substantially in the plane of said wire network when the latter is in a plane and said slats being substantially normal to a diagonal of said meshes and having a width smaller than half of said diagonal and being spaced from each other a distance larger than their width and having adjacent at one of their ends an opening passing therethrough; and fastening means going through said opening for fastening said slats to one of said parallel wires.

6. A fence comprising, in combination, a pair of spaced supporting posts; a pair of spaced substantially parallel wires respectively fastened to and extending between said posts in a direction substantially normal thereto; a wire network extending between said posts and said pair of parallel wires, said wire network being formed by only two endless wires interlaced with each other and said parallel wires and forming quadrangular wire meshes between said parallel wires, and said two endless wires forming a plurality of loops wound about said posts, respectively, and intermeshed with the quadrangular wire meshes adjacent to said posts to fasten said meshes to said posts; and a plurality of spaced slats interwoven between said wire meshes substantially parallel to said posts.

7. A fence comprising, in combination, a pair of spaced supporting posts; a pair of spaced substantially parallel wires respectively fastened to and extending between said posts in a direction substantially normal thereto; a wire network extending between said posts and said pair of

parallel wires, said wire network being formed by only two endless wires interlaced with each other and said parallel wires and forming substantially equal quadrangular wire meshes between said parallel wires, and said two endless wires forming a plurality of loops wound about said posts, respectively, and intermeshed with the quadrangular wire meshes adjacent to said posts to fasten said meshes to said posts; and a plurality of spaced slats interwoven between said wire meshes substantially parallel to said posts, said slats having a width smaller than half of a diagonal of said wire meshes and being spaced from each other a distance larger than their width.

8. A fence comprising, in combination, a pair of spaced supporting posts; a pair of spaced substantially parallel wires respectively fastened to and extending between said posts in a direction substantially normal thereto; a wire network extending between said posts and said pair of parallel wires, said wire network being formed by only two endless wires interlaced with each other and said parallel wires and forming substantially equal quadrangular wire meshes between said parallel wires, and said two endless wires forming a plurality of loops wound about said posts, respectively, and intermeshed with the quadrangular wire meshes adjacent to said posts to fasten said meshes to said posts; a plurality of spaced slats interwoven between said wire meshes substantially parallel to said posts, said slats having a width smaller than half of a diagonal of said wire meshes and being spaced from each other a distance larger than their width and having adjacent at one of their ends an opening passing therethrough; and fastening means going through said opening for fastening said slats to one of said parallel wires.

9. A removable snow fence comprising, in combination, a plurality of adjacent fence sections adapted to be rolled up, each of said fence sections comprising a pair of end posts; a wire network extending between said end posts and fastened to the same, said wire network being formed by a plurality of intermeshed wires forming substantially equal and substantially quadrangular wire meshes connected at the intersection points thereof for relative movement to each other; and a plurality of spaced flexible slats interwoven in and held by said wire meshes, said slats being substantially in the plane of said network when the latter is in a plane and being substantially normal to a diagonal of said meshes and substantially parallel to said posts, said slats having a width smaller than half of said diagonal and being spaced from each other a distance larger than their width.

10. A removable snow fence comprising, in combination, a plurality of adjacent fence sections adapted to be rolled up, each of said fence sections comprising a pair of end posts; a wire network extending between said end posts, said wire network being formed by a plurality of intermeshed wires forming substantially equal and substantially quadrangular wire meshes connected at the intersection points thereof for relative movement to each other; a pair of wire spirals respectively wound about said end posts and interconnected with the wire meshes adjacent to said posts for fastening said network to said end posts; and a plurality of spaced flexible slats inter-

woven in and held by said wire meshes, said slats being substantially in the plane of said network when the latter is in a plane and being substantially normal to a diagonal of said meshes and substantially parallel to said posts, said slats having a width smaller than half of said diagonal and being spaced from each other a distance larger than their width.

11. A removable snow fence comprising, in combination, a plurality of adjacent fence sections adapted to be rolled up, each of said fence sections comprising a pair of end posts; a pair of spaced substantially parallel wires fastened to and extending between said end posts; a wire network extending between said end posts and said pair of substantially parallel wires, said network fastened to said end posts and interconnected to said parallel wires, said wire network being formed by a plurality of intermeshed wires forming substantially equal and substantially quadrangular wire meshes connected at the intersection points thereof for relative movement to each other; a plurality of spaced flexible slats interwoven in and held by said wire meshes, said slats being substantially in the plane of said network when the latter is in a plane and being substantially normal to a diagonal of said meshes and substantially parallel to said posts, said slats having a width smaller than half of said diagonal and being spaced from each other a distance larger than their width and having adjacent at one of the ends thereof an opening passing therethrough; and fastening means going through said opening for fastening said slats to one of said pair of parallel wires.

12. A removable snow fence comprising, in combination, a plurality of adjacent fence sections adapted to be rolled up, each of said fence sections comprising a pair of end posts; a wire network extending between said end posts and fastened to the same, said wire network being formed by a plurality of intermeshed wires forming substantially equal and substantially quadrangular wire meshes connected at the intersection points thereof for relative movement to each other; a plurality of spaced flexible slats interwoven in and held by said wire meshes, said slats being substantially in the plane of said network when the latter is in a plane and being substantially normal to a diagonal of said meshes and substantially parallel to said posts, said slats having a width smaller than half of said diagonal and being spaced from each other a distance larger than their width; and a plurality of wire loops respectively wound about the top ends of adjacent end posts to connect adjacent fence sections to each other.
